BOTTOM PROTECTOR AND REINFORCING
MEANS FOR BOTTLE CASES

John F. Maurer, Jr., North Bergen, N. J.

Application December 6, 1938, Serial No. 244,187

2 Claims. (Cl. 217—69)

This invention relates generally to box structures and refers more particularly to an improved protecting and reinforcing means for the lower edges of the side and end walls of milk bottle cases or the like and especially those provided with corner units of the type disclosed in my prior United States Letters Patent, No. 2,034,440, granted March 17, 1936.

The present invention broadly comprehends protecting and reinforcing means for the lower edges of the side and end walls of a bottle case which is fashioned from a single unitary piece of material and which is so constructed and arranged as to provide smooth, unbroken, streamlined surfaces thereby avoiding edges or projections which would tend to catch or interlock with each other or interfere with the proper conveyance of the cases on conveyor systems which are now generally used in large dairies and bottling plants.

The invention further resides in a protecting and reinforcing means of the indicated character which is constructed and arranged to interlock or interengage with corner units of the type disclosed in the aforesaid prior patent.

As a further feature the invention comprehends a protecting and reinforcing means of the character set forth which possesses greater strength in proportion to the gage of material used, which may be economically produced, which is easier to handle and more readily installed and which is more efficient than those previously employed.

With the above enumerated and other objects in view, the invention is set forth in greater detail in the following specification and illustrated in the accompanying drawing in which:

Fig. 1 is a fragmentary perspective view of the underside of a bottle case provided with a bottom protecting and reinforcing means constructed in accordance with the invention.

Fig. 2 is a perspective view of the bottom reinforcing means removed from the case.

Fig. 3 is a fragmentary enlarged horizontal sectional view taken approximately on the line 3—3 of Fig. 1.

Fig. 4 is a fragmentary vertical sectional view taken approximately on the line 4—4 of Fig. 1.

Fig. 5 is a fragmentary perspective view of the lower end portion of the outer element of one of the corner units.

Referring to the drawing by characters of reference, A and B designate generally the side and end walls of a bottle case which are illustrated in the present disclosure as made up of a plurality of wooden slats although it is to be under-

stood that within the scope of the invention the said walls may be made of a single panel if so desired.

The walls A and B are connected to each other by corner units which include inner and outer angulated elements 10 and 11 which are releasably secured in assembled relation with the case walls by means of a wire or rod 12 which extends through loops 13 directed inwardly from the outer corner elements and received in slots 14 in the inner corner elements as set forth in my prior United States Letters Patent, No. 2,034,440. In the present instance, the outer element 11 of each corner unit is offset outwardly as at 15 and the lower edge of said offset portion is provided with inwardly directed web 16 located between the lower perforated arms 17 which also receive the securing rod or wire 12.

In lieu of the individual channel-shaped runners or strips which have heretofore been employed for protecting and reinforcing the lower edges of the side and end walls of the case, the present invention comprehends a protecting and reinforcing frame, designated generally by the reference character C, which is fashioned from a single unitary piece of material, preferably a flat piece of sheet metal which is blanked and formed as shown to provide integral side and end rails 18 and 19 of channel-shaped construction, each including inner and outer side flanges 20 and 21 joined by a web or bight portion 22. The inner and outer flanges at their juncture with the web or bight portion 22 are preferably rounded and merge into each other to present a smooth, unbroken surface, while the said flanges of the side rails 18 and 19 at their juncture with each other are rounded and merge into each other to present smooth, unbroken surfaces.

The outer flanges 21 of the side and end rails 18 and 19 at their juncture with each other are cut away as at 23 for approximately half of their height and the cut away portions are formed with inwardly offset tongues 24 which, at their juncture with the flanges, are provided with rounded, outwardly offset vertical beads 25.

The protecting and reinforcing frame C is applied so as to fit over the lower edges of the side and end walls A and B with the inwardly offset tongues 24 disposed within the outwardly offset lower ends of the outer angulated elements 11 of the corner units and with the inwardly directed web 16 and the arms 17 received between the upper edges of the cut away portions 23 and the tongues 24, the vertical rounded beads 25 lying alongside of the free edges of the offset portions 55

of the outer elements 11. The protecting and reinforcing frame C is also secured to the walls of the case by the usual bottle supporting rods 21 and by the rivets 28 which secure the center 5 cross brace 29 in place.

From this construction and arrangement it will be appreciated that the bottom of the case is thus protected and reinforced by a frame which presents continuous smooth, unbroken, streamlined surfaces, avoiding any sharp corners, edges or protrusions which would permit of interlocking engagement or interference with the cases on conveyor systems, thereby permitting of the feeding of the cases by said conveyors without jamming.

What is claimed is:

1. In a bottle case having vertical side and end walls and corner units connecting said walls including inner and outer angulated elements, the 20 latter having outwardly offset lower ends, a protecting and reinforcing means for the lower edges of said walls comprising a frame formed of a single unitary sheet of material including integral cross sectionally channel-shaped side and end 25 rails formed with inner and outer flanges embracing the lower edges of said walls, the outer flanges being cut away and slotted at their corners forming a pair of opposed tongues at each corner and said tongues being offset inwardly and 30 interfitted with and against the inner surfaces of the outwardly offset lower ends of the outer elements of the corner units, and with the lower portion of the outer element of each corner unit disposed within the recessed corner areas of the 35 frame provided by the inward offsetting of the

the tongues to thereby dispose the outer surface of the lower ends of the corner units substantially flush with the outer surface of the outer flange of the frame, and the lower ends of the outer elements having inbent continuous flanges 5 fitted in the slots.

2. In a bottle case having vertical side and end walls and corner units connecting said walls including inner and outer angulated elements, the latter having outwardly offset lower ends, a protecting and reinforcing means for the lower edges of said walls comprising a frame formed of a single unitary sheet of material including integral cross sectionally channel-shaped side and end rails formed with inner and outer flanges 15 embracing the lower edges of said walls, the outer flanges being cut away and slotted at their corners forming a pair of opposed tongues at each corner and said tongues being offset inwardly and 20 interfitted with and against the inner surfaces of the outwardly offset lower ends of the outer elements of the corner units, and with the lower portion of the outer element of each corner unit disposed within the recessed corner areas of the 25 frame provided by the inward offsetting of the tongues to thereby dispose the outer surface of the lower ends of the corner units substantially flush with the outer surface of the outer flange of the frame, and the lower ends of the outer 30 elements having inbent continuous flanges fitted in the slots, and vertical outwardly convex beads formed at the juncture of the tongues with the flanges to shield the side edges of the offset lower ends of the outer elements of the corner units.
